United States Patent Office.

GARRETTSON SMITH AND HENRY BROWN, OF PHILADELPHIA, PENNSYLVANIA, ASSIGNORS
TO WILLIAM FLESH AND J. J. ROEPPER, OF SAME PLACE.

Design No. 2,985, dated March 31, 1868.

DESIGN FOR A COOK'S STOVE.

The Schedule referred to in these Letters Patent and making part of the same.

TO ALL WHOM IT MAY CONCERN:

Be it known that we, GARRETTSON SMITH and HENRY BROWN, of the city and county of Philadelphia, and State of Pennsylvania, have originated a new and original Design for Cooking-Stoves, of which the following is a full and exact description, reference being had to the accompanying photographs, making a part of this specification.

Figure 1 is a perspective view of the stove.

Figure 2 is a like view of the back plate detached from the stove.

On the upper rail *a* of the sides *A* of the stove is the name "Relief Complete," and on the lower rail the date of the patent, viz, "Patented March 10, 1868." The oven-doors *B* have raised panels *C* with wreaths *D*, which have alternately groups of cross elliptical-shaped beads *b* and leaves *c*. There is a wreath, *E*, of leaves inside of the wreath *D*. There is a raised central ornament, *F*, within the wreath *E*, composed of elliptical projections *d*, with a central leaf-ornament, *e*. The wreaths *D* and *E*, and the central ornament *F*, are of elliptical form. There are corner leaf-ornaments *G*. The front plate, above the fireplace, has a similar ornamentation to that of the oven-doors *B*, with the addition of leaf-ornaments *f f*, arranged between the corner ornaments *G* vertically. At the ends of the plate there are vertical ornaments *g*, which run from the bottom to the top edge of the plate. The small side-doors *H* have, on their raised panels *C'*, a wreath, *D'*, similar to the wreath *D* of the oven-doors *B*, and similar corner ornaments *G*. Within the wreath there is a vine, *h*, over the elliptical bead *i*, and within the circumference of the bead an elliptical ornament, *J*. The front fire-doors *K* have similar ornamentation to the oven-doors *B*, with the exception that in the latter the wreath *E* is omitted. The stiles *j* of the fire-front *L* have vertical bead and dot-ornaments, *j'*. The feet *M* have a double scroll, *k*, at top, an ornament, *l*, beneath it, and beads *m* and dots *n* continued to the toe. The front edge of the top plate *N* has a leaf-ornament, *o*. The feed-door *O*, crosswise, is of elliptical form, and has cross-openings *p*. Above the fire-door *K* are the words "Relief Complete," followed by the figure which designates the size of the stove. On the back plate *P*, which is represented in fig. 2 detached from the stove, there are three vertical ornaments, *q*, in square panels *r'*, and near the bottom edge of the plate is the name and place of the firm, viz, "Flesh & Roeper, Philadelphia."

What we claim as our invention, and desire to secure by Letters Patent, is—

The design for cooking-stoves, as shown and described.

In testimony that the above is our invention or discovery, we have hereunto set our hands and affixed our seals, this fifth day of March, 1868.

GARRETTSON SMITH. [L. S.]
HENRY BROWN. [L. S.]
